ATTORNEY

UNITED STATES PATENT OFFICE.

ROMANO ROSA, OF LOUISVILLE, KENTUCKY.

WALL-CLEANER.

1,044,423.

Specification of Letters Patent. Patented Nov. 12, 1912.

Application filed May 31, 1912. Serial No. 700,904.

To all whom it may concern:

Be it known that I, ROMANO ROSA, a citizen of the United States, residing at Louisville, in the State of Kentucky, have invented a new and Improved Wall-Cleaner, of which the following is a specification.

My invention relates particularly to wall cleaners driven by motors mounted on a movable stand and has for its object to improve the structure and efficiency thereof.

It consists of novel features and parts and combinations of the same which will be more fully described hereinafter and then pointed out in the claim.

A practical embodiment of my invention is shown in the accompanying drawings, in which—

Figure 1 is a vertical longitudinal cross-section of my device, partly in elevation; Fig. 2, an end elevation thereof; and Fig. 3, a detail sectional view on the line 3 3 of Fig. 1.

My invention consists essentially in associating on the shaft of a motor a fixed driving wheel and a swinging arm provided with a second shaft and driving wheel on said arm at the operating point.

It further consists in mounting said motor on a movable truck, in making said arm adjustably extensible to facilitate the placement and adjustment of the driving chain, and in providing a handle on the outer part of said arm for controlling the same.

The motor 2 is mounted on the movable truck 1 and is provided with the shaft 3. To the shaft 3 is fastened the main driving wheel 5, preferably a sprocket wheel, with its hub slipped over the sleeve 4. The sleeve 4 is adapted to contain the balls 6 which form a ball-bearing for the arm 7. The arm

7 has an adjustable extension 8, which is fixed by the set-screw 11 being tightened into one of the teeth 10. This adjustment allows the sprocket chain 17 to be readily tightened or removed. The extension 8 is provided with a handle 9 near the operating position. Preferably at its end is placed the secondary shaft 12, driven by the secondary sprocket wheel 13. To give perfect adjustment to the wall 18, the container 15 for the cutting or cleaning instrument 16 is connected to the shaft 12 by the universal joint 14.

My device is particularly adapted to mosaic work where considerable cutting has to be done, and it is evident that the entire surface of a vertical wall can be readily covered by simply moving the truck along parallel thereto at the proper distance therefrom. This gives great rigidity to the cleaning or cutting tool in its bite on the wall without pushing strain on the part of the operator and makes it simply necessary for him to overcome gravity when the arm 7 is in an oblique position.

I do not limit myself further than is indicated in the claim which follows.

I claim:

A motor provided with a shaft, an extensible arm on said shaft rotatable independently thereof, a sprocket wheel on said shaft, a sprocket wheel and shaft and rotary cleaner on said arm, and a continuous chain connecting said sprocket wheels and adapted to drive said cleaner.

ROMANO ROSA.
